No. 657,127.

Patented Sept. 4, 1900.

W. MITCHELL.

VAPOR BURNING LAMP.

(Application filed Apr. 5, 1899. Renewed July 20, 1900.)

(No Model.)

UNITED STATES PATENT OFFICE.

WILLIS MITCHELL, OF MALDEN, MASSACHUSETTS, ASSIGNOR, BY MESNE ASSIGNMENTS, TO THE MITCHELL GAS GENERATOR AND BURNER COMPANY, OF NEW JERSEY.

VAPOR-BURNING LAMP.

SPECIFICATION forming part of Letters Patent No. 657,127, dated September 4, 1900.

Application filed April 5, 1899. Renewed July 20, 1900. Serial No. 24,333. (No model.)

To all whom it may concern:

Be it known that I, WILLIS MITCHELL, a citizen of the United States, residing at Malden, in the county of Middlesex and State of Massachusetts, have invented certain new and useful Improvements in Vapor-Burning Lamps; and I do hereby declare the following to be a full, clear, and exact description of the invention, such as will enable others skilled in the art to which it appertains to make and use the same.

This invention relates chiefly to lamps using gasolene or similar vapor and having a chamber which supplies the burner and a generating tubular coil that discharges into the same.

The said invention consists in the construction and combination of parts hereinafter more particularly set forth and claimed.

In the accompanying drawings, Figure 1 represents a vertical central section of a lamp embodying my invention. Fig. 2 represents in perspective the alcohol cup or bowl of the said lamp and some of the parts immediately attached thereto or in contact therewith. Fig. 3 represents a detail view of the cover for this cup or bowl. Fig. 4 represents a detail view of the mixing-chamber. Figs. 5 and 6 represent detail views of the base of the said chamber. Figs. 7 and 8 represent detail views of successive outer shells. Fig. 9 represents a detail perspective view of the rack which carries the regulator-needle and the guides for said rack. Fig. 10 represents a detail view of the deflector arranged within the burner-screen, and Fig. 11 represents a detail view of the said screen with the deflector in place.

A designates a broad hollow base, preferably of sheet metal or cast metal, which may be either rectangular or circular in shape and serves also as a gasolene-reservoir. This is filled through an oil-inlet A', into which is fitted the tubular stem of a cup or low funnel A². Said stem is internally threaded to receive the correspondingly-threaded solid stem a' of a stopper a, the top of which closes the top of the cup. The upper part of this base or reservoir A is formed into a hollow dome A³, which is provided with an air-inlet tube a³,

internally screw-threaded to receive the correspondingly-screw-threaded stem a⁵ of an air-vent plug a⁴, having an air-passage a⁶ through it. This passage is turned laterally at its lower end through the side of the said stem, so that air may pass through the said plug to the interior of the said dome and base while the said plug is in the position shown in Fig. 1; but the inlet will be closed when the solid lower end of the stem a⁵ is turned down against the lower part of the tube a³, which is so formed as to leave an opening much smaller than the main bore of the said tube. The outer part of the said plug is adapted to receive a rubber bulb, by the compression of which air is driven into the reservoir A, forcing the gasolene up through a vertical tube W, which is slotted at its lower end and arranged within a vertical tube B. A cylindrical coupling-block C has a small central bore c in its middle part and a recess C' in its lower end, into which the upper end of the tube B is fitted. In the upper end of the said coupling-block is another recess C² of about the same length as C', but of slightly-greater diameter, as shown. The wall of this is internally screw-threaded to receive the correspondingly-threaded stem D' of an alcohol cup or bowl D. The lower end of the said recess is conical to receive a similarly-shaped filling-block E. These parts D' and E have a coincident central vertical bore practically continuous with that of the coupling-block C, so that a gasolene-tube F, about one-sixteenth of an inch in diameter, is carried up through the said coupling-block and stem and above the oil in the said cup or bowl D to form a double generating-coil G about the mixing-chamber H. A tubular column I, concentric with tube C, extends up from the dome A³ to the alcohol-cup D, being rigidly secured at both ends. This column fits the exterior of coupling-block C and also at its lower end on a cylindrical socket or bushing A⁴ of the dome A³, which is interposed between the lower end of the said column and the corresponding part of tube B and braces both, making a strong stem for the lamp. A concave cover I⁸, provided with a cylindrical

- hollow upward extension I' and legs or brackets I², is supported by the said cup. These legs or brackets are notched at i on the under side to fit on the upper edge of said cup.
- 5 They are also preferably of greater thickness and strength than the said cover and support the rods J of an ordinary shade-frame surrounding the dome-shaped reticulated burner K of the lamp. This burner, preferably of 10 finely-woven wire, is mounted on the top plate H' of the cylindrical mixing-chamber H, before mentioned, said plate being circumferentially enlarged to receive it. A cylindrical shell or jacket H², of diameter slightly 15 greater than that of the top plate, extends down from the said top plate to the cover I' and is fastened by screws k to the cylindrical upward extension I' of the said cover, these parts I' and H² being arranged concentrically.
- 20 The peripheral part of the said top plate rests on the upward extension I', and the upper edge of the jacket H² is bent over at k' on the peripheral part of the said burner above the said top plate to hold the said burner in place.
- 25 The said top plate has a central outlet H³ formed therein and extended upward in the form of a short tube, discharging the contents of the mixing-chamber into a cap or deflector L, preferably of sheet metal, suspended 30 rigidly over the said tube from the underside of the raised center of the said dome-form burner. This deflector or cap allows the air and vapor to mix more thoroughly before escaping, then directs them downward and laterally, so that they pass out at its periphery, 35 and at last escape through the many small holes in the said burner for ignition. The base M of the said mixing-chamber consists of an upper disk-shaped part having a series 40 of inlet-holes m formed through it, which admit the air from below to the interior of the mixing-chamber, and a screw-threaded stem N, having a central inlet-bore n, extended through the center of the said disk and receiving from a nozzle or end h² of the generator-coil a supply of gasolene-vapor, which 45 passes from the said bore into the said mixing-chamber. This supply is governed by a needle-valve O working up through the said 50 bore to close or open the said nozzle at will, said valve being carried by a rack P, which is engaged by a pinion Q on a transverse regulating-shaft R, mounted on the top of the said alcohol-cup and provided with an exterior 55 knob or milled head for convenience of operation. Said rack moves up and down in guideways S, fastened rigidly by arms T to the said alcohol-cup.
- The alcohol is supplied by a supplementary 60 reservoir U in the main reservoir or base A through an alcohol-pipe V, which extends upward through the bushing A⁴ and coupling-block C aforesaid and follows the curvature of the exterior of the alcohol cup or bowl D, 65 its upper bent end v passing in through the side of said bowl D to the interior thereof, as shown. The tubes and the several parts to

which they are attached are preferably soldered together.

To force out the alcohol at will, I preferably employ a piston X, operated by a rod Y, the said rod having a limited independent movement in a tubular stem z of the said piston, such movement being limited by a stoppin y. The said stem is provided with a hole 75 z' at the side which admits alcohol to the bore of the said stem, and thereby to the space below the said piston when the said rod is raised, but is closed by the downward motion of the rod. The piston moves up with the 80 rod after the said hole is uncovered and down with the rod after the said hole is closed, the alcohol being forced thereby out through the tube V, which makes connection with the bottom of the alcohol-reservoir.

85

The needle-valve O passes through a stuffing box or gland Z, which is screw-threaded internally to engage the external screw-threads of the stem N and provided with suitable packing that surrounds the said needle-valve, being forced into the concavity n at the end of the said stem on screwing up the said gland.

90

An external cylinder or casing Z', slightly flaring at the top and bottom, surrounds the 95 casing, shell, or jacket H², leaving an air-space between them to prevent overheating the outer casing or cylinder Z', which there is often occasion to touch. The small diameter of the generator-tube is found exceedingly efficacious. I can increase or diminish the amount of pressure by varying the length of the said generator. This is usually about thirty inches and should not be as short as eighteen inches to be reliably operative. The 100 diameter must not be varied more than one thirty-second part of an inch or the result may not be satisfactory.

105

The operation is as follows: The base A being supplied with gasolene and the supplemental alcohol-reservoir with alcohol, the latter is forced, as described, up through the pipe V to the cup or bowl D. The alcohol is then ignited, heating the generator. After it has been burning for about thirty seconds 110 the needle-valve O is withdrawn, allowing the heated air in the coil to escape into the mixing-chamber, and thus admitting the gasolene to the generating-coil, and the vapor thus produced is discharged into the mixing-chamber through the passage before described. It there becomes mixed with the air entering through holes m. The heated mixture of gasolene-vapor and air passes up 115 through the burner, being more thoroughly commingled in and by the deflector on the way, and is ignited as it issues through the said burner. This creates a draft up through the generator and mixing-chamber, continuously supplying the said burner until the needle-valve is raised to cut off the supply of 120 gasolene.

125

A mantle-supporting rod J² passes through a guiding-perforation in one of the legs or

130

brackets I² and is set at its lower end into or through the support T. An adjusting-screw J³, working through the side of cup D, bears against the said rod or support J³ and affords 5 a convenient means of holding the mantle at any point, within certain limits, to which it may be adjusted vertically. This rod, if desired, may be extended through the said cup, its joint therewith being made liquid-tight, 10 as must also be done with that of screw J³.

Having thus fully described my invention, what I claim as new, and desire to secure by Letters Patent, is—

1. In combination with a mixing-chamber 15 having inlets for air and vapor and an outlet for the same when mixed, a generator surrounding the said chamber and supplying it through one of the said inlets, an alcohol-cup below the said chamber, a cover for the said 20 cup provided with a central cylindrical hollow upward extension surrounding the said generator, and a wire-gauze or perforated burner covering the top of the said chamber, substantially as set forth.
2. In combination with a mixing-chamber 25 having inlets for air and vapor and an outlet for the same when mixed, a generator surrounding the said chamber and supplying it through one of the said inlets, an alcohol-cup 30 below the said chamber, a cover for the said cup provided with a central, cylindrical, hollow, upward extension surrounding the said generator, a wire-gauze or perforated burner covering the top of the said chamber and fastened on the same, and a deflector suspended 35 from the said burner over the outlet of the said mixing-chamber, substantially as set forth.
3. In combination with a mixing-chamber 40 having inlets for air and vapor and an outlet for the same when mixed, a generator consisting of a fine, tubular wire coil about one-sixteenth of an inch in diameter wound around the said mixing-chamber and dis- 45 charging into the same, an alcohol-cup below the said mixing-chamber and generator, and a cover for the said cup having a cylindrical upward extension surrounding the said generator and closed at its upward end by a hori- 50 zontal annular extension of the top of the said mixing-chamber, substantially as set forth.

4. In combination with a mixing-chamber having inlets for air and vapor and an outlet for the same when mixed, a generator sur- 55 rounding the said chamber and supplying it through one of the said inlets, a cup adapted to receive alcohol and arranged below the said chamber to heat the said generator when the liquid contained in said cup is ignited, a

burner supplied by the said chamber, a cover 60 for the said cup provided with a central cylindrical hollow upward extension external to the said generator, means for supplying liquid to the said cup and the said generator, and two concentric casings arranged outside 65 of the said cylindrical extension, each having an interval between it and the part next within, substantially as set forth.

5. In combination with a mixing-chamber for air and vapor, having an opening for the 70 admission of air, a base for the said chamber having a small, central bore and a branch passage therefrom, a generating-coil which is wound about the said chamber and has its discharging end fitted into the said branch 75 passage, a needle-valve working up and down in the said bore, means for supplying gaso- 80 lene to the said generator, mechanism for raising and lowering the said needle-valve, guideways for the said valve and an alcohol- 85 cup provided with supports for the said mixing-chamber and the said guideways, sub- stantially as set forth.

6. In combination with a mixing-chamber, a burner supplied thereby and a generator 85 supplying vapor to the said chamber, an alcohol-cup arranged to heat the said generator and cause it to supply the said chamber with vapor, a cover for said cup, feet or brackets 90 for said cover which are notched or recessed to fit on the edge of the said cup and adapted to support a shade-frame and means for sup- 95 plying liquid to the said cup and generator, substantially as set forth.

7. In combination with a mixing-chamber, 95 burner and generator arranged substantially as described, an alcohol-cup arranged below them to heat the generator and supply the chamber, and provided with a downwardly- 100 extending stem having a central bore, a re-cessed and bored coupling-block screwing on the said stem, a tube fitting into the lower end of the said coupling-block, a tubular col- 105 umn supporting the said cup, arranged con- centric with the said tube and exterior to the said coupling-block, a base having a raised tubular part which fits between the said col- umn and the said tube, and conduits for the 110 alcohol and the liquid which supplies the generator, extending up within the said column, substantially as set forth.

In testimony whereof I affix my signature in presence of two witnesses.

WILLIS MITCHELL.
